DESIGN FOR A BEVERAGE DISPENSING UNIT

Raymond T. Moloney, Chicago, Ill.

Application July 17, 1933. Serial No. 48,740

Term of patent 3½ years

To all whom it may concern:

Be it known, that I, RAYMOND T. MOLONEY, a citizen of the United States, residing at Chicago, in the county of Cook, and State of Illinois, have invented a new, original, and ornamental Design for a Beverage Dispensing Unit of which the following is a specification, reference being had to the accompanying sheet of drawing, forming part thereof.

Figure 1 is a perspective view of the beverage dispensing unit as viewed from the front; and,

I claim:

The ornamental design for a beverage dispensing unit, as shown and described.

RAYMOND T. MOLONEY.
